UNITED STATES PATENT OFFICE

HARRY B. BARKER, OF CHICAGO, ILLINOIS, ASSIGNOR TO MOTOGRAPH CORPORATION OF AMERICA, OF CHICAGO, ILLINOIS, A CORPORATION OF ILLINOIS

DISPLAY DEVICE

Application filed January 19, 1928. Serial No. 247,918.

This invention relates to display devices and more particularly to display devices of the illuminated type which have an endless traveling light transmitting belt, a portion 5 of which is interposed between a light source and a visible screen bearing indicia formed by perforations therethrough.

The main objects of this invention are to provide a display device of this character 10 wherein a portion of the length of the traveling belt is provided with perforations therethrough so that light may pass through said perforations to a visible screen bearing indicia likewise formed by means of perforations 15 through it; to provide improved means for driving the endless belt; to provide an improved set of rollers on which the traveling belt is carried; to provide an improved form of mounting for the mechanism used to rotate one of the rollers; to provide improved means 20 for flexibly tensioning the traveling belt; and, to provide an improved form of magazine or housing for the operating mechanism.

An illustrative embodiment of this invention is shown in the accompanying drawings wherein:

30 Figure 1 is a top plan view of the display device with the cover thereof removed.

Fig. 2 is a fragmentary front elevation of the display device.

Fig. 3 is a sectional view thereof taken on line 3—3 of Fig. 1.

Fig. 4 is a sectional view thereof taken on line 4—4 of Fig. 1.

Fig. 5 is another sectional view of the display device taken on line 5—5 of Fig. 1.

40 Fig. 6 is likewise a sectional view thereof taken on line 6—6 of Fig. 1.

In the specific form herein shown, the display device comprises a housing in which is located an endless belt having a plurality of perforations throughout a portion of its length, the belt being carried on a plurality of rollers. A screen bearing indicia formed by perforations therethrough is visible on the front side. A source of light such as a 45 battery of incandescent globes is provided

within the housing, which battery is encircled by the traveling belt. An improved form of a friction drive roller operated by a motor mounted in an improved manner is provided for moving the belt on the rollers and an improved form of tensioning mechanism is provided for flexibly tensioning the belt during 55 its travel. A reflector is provided at the rear of the battery of incandescent lamps for reflecting the light through the perforations on 60 the traveling belt and thence through the perforated indicia in the visible screen.

In the specific form herein illustrated, the improved display device comprises a magazine or housing 1 in which is located a traveling vertically disposed endless belt 2 carried in a vertical edgewise position by rollers 3, 4, 5 and 6. The traveling belt is flexible and preferably of specially treated cloth. Substantially one half of the length of the belt 65 has a plurality of perforations 51 throughout its width through which light from any suitable source, such as a battery of incandescent lamps 7, is permitted to pass.

The magazine or housing 1 may be of any 70 suitable material but is preferably made of sheet metal having a base 8 on which is mounted the several belt carrying rollers. These rollers are all disposed vertically within the several four corners of the rectangular magazine or housing 1, the roller 4 being driven by 75 motor 9 through reduction gearing herein-after more particularly described, and the roller 6 is tensionally and flexibly spaced from the driven roller 4 by means hereinafter more 80 particularly described.

Secured to the base 8 and interposed between the battery of incandescent lamps and the back side of the magazine or housing is a canopy 10 forming a reflector. Secured with 85 in the channel frame members 11 which are secured to the base 8, and between the battery of incandescent lamps and the traveling belt, is a translucent diffusing screen 12 which evenly distributes the light from the lamps 7. 90

A stationary screen 13 of cardboard or the like bears indicia such as advertising matter, the lettering being formed in this instance by double parallel rows of perforations 14. This stationary screen is secured within chan- 100

nel frame 15 secured to the base, and between the traveling belt and the light transmitting screen 16. This stationary screen is visible to the on-looker and forms the front side of the magazine or housing.

5 Rear legs 17, secured to the base 8 of the magazine or housing, are shorter than the U-shaped metal legs 18 which are likewise secured to the base 8 adjacent the front edge thereof. The front side of the display device, 10 when in use, is thus inclined upwardly.

15 The motor 9 has a worm 19 meshing with a gear 20 fixed to the upper end of a shaft 21. This shaft is journaled in a bearing 22 mounted on the motor frame and a gear 23 is fixed to the lower end of the shaft 21. The gear 23 meshes with a gear 24 which is secured to the lower end of the driven roller 4.

20 The roller 6 is journaled in a yoke 25 having its lower end provided with a stud 26 shiftable horizontally in a slot 27 formed in the base frame 8. A vertically disposed bracket 28 is provided with a horizontally disposed foot 29 on the lower end thereof which has a slot 30 therein. An upstanding bolt 31 is secured to the base 8 of the magazine and projects vertically through the slot 30 for adjustably positioning the bracket 28. A wing nut 32 provides means for securing the bracket 28 in adjusted position. The yoke 25 is mounted on the bracket 28 by a horizontally disposed stud 34 rigidly secured to the medial part of the yoke 25. The stud 34 is slidably mounted in the bracket 28 and is normally urged outwardly from said bracket by a helical compression spring 33 which surrounds the stud 34. This spring 33 serves to tensionally and flexibly space the yoke from the bracket and a pin 40 transversely mounted in 40 the outer end of the stud 34 retains said bracket stud in assembled relation to the bracket 28. Thus the traveling belt may be frictionally revolved by means of the driven roller 4 on the rollers 5, 6 and 3, and the tension on the belt may be regulated by means of the wing-nut 32 which adjustably secures the bracket 28 to the base 8.

45 A frame 35 for the front of the display device is provided with a window 36. This frame is rigidly secured to the side walls 37 of the magazine as by screws 38 passing through brackets 39 which are welded or otherwise secured to said side walls.

50 In operation the endless belt 2 is revolved 55 on the rollers 3, 4, 5 and 6 by means of belt friction on the driven roller 4 and the belt tensioning roller 6. The belt moves in the direction of the arrows and inasmuch as only substantially one-half of the length of the 60 belt is provided with perforations, indicia on the stationary screen 13 is increasingly visible from the left to the right during the travel of the belt and then diminishingly visible in the same direction. It will thus be 65 seen that the indicia on the stationary screen

is alternately sometimes wholly visible and sometimes totally invisible. The light in passing through the translucent screen 12 is diffused. This diffuses the indicia on the stationary screen when the same is visible, 70 giving to the indicia a twinkling or scintillating effect. The screen 12 may be varicolored to produce different color effects on the stationary screen and the screen 16 may be sandblasted or otherwise treated to provide 75 varying forms of visibility.

80 While but one specific embodiment of this invention has been herein shown and described, it will be understood that numerous details of the construction shown may be altered or omitted without departing from the spirit of this invention as defined by the following claim.

I claim:

85 In a device of the class described, a housing vertically disposed rollers mounted on the base of said housing, one of said rollers being shiftable horizontally, an endless belt carried by said rollers, means for rotating one of said rollers to revolve said belt, and means 90 for tensioning the belt comprising a yoke connected to the upper and lower ends of said shiftable roller, an upright bracket having a pin and slot connection with said base, a stud rigidly mounted on said yoke and slidably 95 engaging said bracket and a spring interposed between said bracket and yoke and embracing said stud for flexibly spacing the rollers apart.

95 Signed at Chicago this 17th day of January, 1928.

HARRY B. BARKER.
